UNITED STATES PATENT OFFICE.

EDWIN CALDWELL, OF NEW YORK, N. Y.

CLUTCH PENCIL.

Application filed December 22, 1922. Serial No. 608,435.

This invention relates to pencils and particularly to the type of pencils having a stick of lead movable within a holder and clamping devices for gripping the lead-stick and holding it with its end projecting slightly beyond the end of the holder. In prior pencils of this type in which a plurality of lead sticks are contained in the barrel of the pencil and fed successively into the gripping or clamping device, the lead sticks have had a tendency to join or bind upon one another with a result that the feeding of the lead sticks to the gripping or clamping device automatically could not be depended upon. The gripping or clamping devices, therefore, commonly employed, and which utilize clamping jaws formed by slitting a tube or sleeve lengthwise for a portion of its length engage and hold the lead along but a short portion of its length, with the result that the lead-stick in use frequently breaks off causing waste, delay and annoyance in the use of the pencil. In order to hold the lead from turning, resort has been had to scoring, grooving or indenting thereof by the clamping device, but this always weakens the lead and causes it to break frequently at the weakened points when pressure is applied to the writing end thereof.

An object of the invention is to provide an improved pencil in which a plurality of leads carried therein may be fed successively through the clamping or gripping device by gravity and without jamming or sticking; with which the danger of breakage of the lead-sticks is reduced to a minimum; in which the lead-sticks are securely held against endwise displacement or turning without weakening the sticks; which may be easily and quickly filled or charged with a fresh supply of leads; which has a maximum possible capacity of lead-sticks at each loading or charging; which may be given any desired finish; which is simple, strong, durable and inexpensive in construction, convenient and practical in use, attractive in appearance, and well balanced; and which encourages refilling with erasers and leads marketed by the concern marketing the pencil.

Other objects and advantages will be ap-

parent from the following description of an embodiment of the invention, and the novel features will be particularly pointed out hereinafter in claims.

In the accompanying drawing:

Fig. 1 is an elevation of a pencil constructed in accordance with the invention;

Fig. 2 is a longitudinal sectional elevation of the same;

Fig. 3 is an enlarged longitudinal sectional elevation of a portion of the same, showing the feeding of the leads from the magazine to the lead gripping device;

Fig. 4 is a transverse section of the same taken substantially along the line 4-4 of Figure 3;

Fig. 5 is another transverse section of the same taken substantially along the line 5-5 of Figure 3;

Fig. 6 is an elevation of the magazine before it is inserted into the barrel of the pencil;

Fig. 7 is an end elevation of the same and showing the slit cap;

In the embodiment illustrated in figures 1 to 7, a sleeve is provided with an end 2 of reduced diameter which is secured within one end of a casing 3 of suitable material, preferably metal, such as brass. The sleeve may be secured therein by solder, welding, or in any other suitable manner. The exposed portion of the sleeve is provided with a reduced annular peripheral groove 4, and upon the outer end thereof with screw threads 5. A plurality of jaws 6 are secured within the outer end of the sleeve 1 so as to form an extension thereof, the jaws having between them a passage 7 of substantially uniform cross section throughout its length and of a size to slidably receive a marking pencil lead-stick such as is commonly used in clutch pencils. The jaws are formed separately, such as by die stamping, and their combined outer surface, when assembled, is tapered in a direction away from the sleeve, to substantially an edge at the outer end.

A tubular cap has a tapered inner wall corresponding substantially to the taper of the outer surface of the assembled jaws, fits over the assembled jaws, and at its larger end has screw threaded engagement with the

screw threads 5 of the sleeve 1. When the cap is adjusted upon the sleeve by means of its screw threaded connection therewith, it is adapted to compress the jaws and cause 5 them to grip or clamp a pencil lead-stick 9, which may be disposed between them, for a considerable distance which is preferably at least the major portion of the length of the jaws. When the cap 8 is unscrewed, the 10 tapered inner wall thereof will release the jaws, which because of their resiliency will spring apart slightly and release the lead 9. The lead can then be adjusted by gravity 15 along the passage between the jaws so as to project from the jaws the desire dextent.

When the cap 8 is screwed upon the sleeve to a greater extent the jaws will be compressed to clamp or grip the lead 9 along a considerable length thereof and securely 20 hold it against rotation and endwise movement in the passage between the jaws, without scoring, indenting or otherwise injuring the lead in such a manner as to cause it to break when pressure is applied to the 25 outer tip thereof. If desired, the large end of the cap may be spun or otherwise flanged inwardly into the annular groove 4 so as to prevent the complete removal of the cap from the sleeve, but at the same time permit 30 of a considerable adjustment upon the sleeve sufficient to clamp or release the lead 9. The jaws and cap together comprise what may be hereinafter referred to as a lead gripping device.

35 The end of the casing 3 opposite the gripping device is open, and a magazine or cartridge 10 is adapted to be inserted or removed from the casing through the open end thereof, the magazine being of a size to fill the interior of the casing from the gripping device to the open end and to project a short distance outwardly from the open end. The magazine 10 may be constructed of any suitable material such as fibre or metal and at 40 the end first inserted into the casing of the pencil it is reduced somewhat in cross section, as at 11. The extreme end of the reduced extension is bevelled inwardly a short distance so as to provide a frusto-conical 45 inturned annular flange 12.

50 A cap 13 of thin metal, such as tin, is fitted over the reduced extension 11 of the magazine and is provided with a flat end 14 which lies entirely or substantially in a plane transverse to the longitudinal axis of the magazine. The inner end of the sleeve 1 is bevelled inwardly in a direction away from the magazine so as to provide a tapered annular seat 15 against which the cap 55 13 may be forced when the magazine is inserted into the casing of the pencil and rammed or otherwise pushed firmly against the annular seat 15.

55 The end 14 of the cap is provided with a plurality of intersecting slits 16, radiating

outwardly from an interior point of the end of the cap, so that when the cap is forced against the annular seat, an annular peripheral portion of the end of the cap will be forced against the flanged seat 12, which will 70 distort the end of the cap into a shape substantially conical and result in a separation of the pointed tongues 17 formed by the intersecting slits. The outward bending of the tongues 17 in this manner will cause 75 them to separate at the interior point of intersection of the slits and produce an opening through which a plurality of reserve leads carried in the magazine may pass successively to the lead gripping device which 80 is secured in the end of the barrel or casing. The slits 16 are so placed in the end 14 of the cap that when the opening is formed by the separation of the tongues 17, it will be in alignment with the passage 7 between the 85 jaws of the gripping device, so that the leads may pass freely from the magazine into the passage 7.

A bushing or sleeve 18 is preferably provided in the end of the magazine which is closed by the cap 13, and its inner wall or passage 19 is eccentric to the outer periphery thereof, and eccentric to the axis of the passage 7 of the gripping device. A longitudinal portion of the wall of the passage 95 19, however, is in alignment with a longitudinal portion of the wall of the passage 7, so that when a lead is positioned against that portion of the wall 19 which is in alignment 100 with the passage 7, the lead will be aligned directly with the passage 7 and can pass freely into the latter. I have found that by this placing of the wall 19 in the portion of the magazine from which the leads pass to the gripping device, the leads will not jam when 105 being fed through the aperture in the magazine to the gripping device, but will pass successively and freely from the magazine to the gripping device. The leads carried in the magazine are disposed not only within the sleeve or bushing 18, but also in the chamber of the magazine beyond the bushing or sleeve 18, and as the pencil is turned while writing, the leads will pass from the 110 large chamber of the magazine into the passage 19 within the sleeve or bushing 18.

115 The magazine is provided with peripheral flange or rib 20 which is adapted to abut against the outer end of the casing 3 when the magazine has been forced into the casing to the maximum possible extent. The magazine extends outwardly beyond the rib 20 for a short distance and has internal screw threads which receive the threaded end 21 of an eraser ferrule 22. An eraser 120 23, such as of rubber or a rubber composition, is secured in the outer end of the ferrule so as to extend therefrom a short distance.

125 A protective cap 24 is adapted to be fitted 130

over the outwardly extending end of the magazine and abut against the rib or flange 20 for concealing the eraser end of the magazine when the use of the eraser is not desired. The protective cap 24 is of the same material as the casing and is preferably given a finish similar thereto, so as to present an attractive appearance. While the eraser ferrule and eraser serve to close the outer end of the magazine 10, I preferably also close the outer end of the magazine 10 by a disc 25 which is secured therein in any suitable manner, such as by forcing the disc into the magazine under pressure.

When the eraser is worn down substantially to the ferrule, the ferrule may be removed from the casing and replaced by another ferrule and eraser, or the eraser may be removed from the ferrule and replaced by a new eraser, which is forced therein.

When the pencil is to be used, a magazine 10 containing a supply of leads is inserted into the open end of the casing 3 and pushed firmly against the seat 15 of the sleeve 1 so as to open the magazine and allow the leads 9 contained therein to feed by gravity successively into the passage 7 between the jaws 6 of the gripping device. When the jaws are released by unscrewing the cap 8 to some extent the leads will drop by gravity into the passage 7 if the pencil is held in a substantially vertical position with the cap 8 at the lower end. When one of the leads has passed along the passage 7 so as to extend beyond the cap 8 to the desired extent, the cap 8 may be tightened upon the sleeve 1 so as to force the jaws together and securely and effectively clamp the lead along a considerable portion of its length, which prevents endwise displacement of the lead and also turning thereof within the passage 7. The pencil may then be used in the usual manner to mark with the projecting end of the lead 9, and because of the conscious or unconscious turning of the pencil by the writer, the lead 9 will always be turned accordingly and consequently will always be pointed or sharp. The same turning movement will cause descent of the lead-sticks from the upper part of the magazine into the sleeve 18 at the lower end thereof to replace those that pass from the latter into the gripping or clamping device at intervals. By uniformly clamping the lead-stick in use for a considerable portion of its length, which preferably may be that portion between the outer ends of the jaws and the sleeve 1, the lead-stick will be firmly gripped or clamped against both turning and endwise displacement, without producing indentations or scorings therein which would tend to cause it to break off at the point of indentation or scoring when pressure is applied to the point in writing.

When the projecting end of the lead is worn down, the cap 8 may be loosened sufficiently to allow the lead to descend to a further extent and then be tightened to again clamp it against turning and endwise displacement. As the lead is used up, other leads in the magazine will descend into the passage 7 behind it and will replace it as the preceding lead is entirely worn out and removed. By having a portion of the wall of the magazine in substantial alignment with a portion of the wall of the passage into which the leads are to be fed, jamming of the leads will be effectively prevented and the leads will under the influence of gravity, descend successively and freely into the passage 7 of the gripping device.

When all of the leads have been used, the magazine may be removed by pulling it from the open end of the casing, discarded, and replaced by a new magazine with a fresh supply of leads. The new magazine is placed in the casing 3 and its end with the cap 13 is forced against the bevelled or conical seat 15 of the sleeve 1, so as to open the magazine and allow the contained leads to pass into the gripping device. If an erasure is to be made the pencil serves as a holder for the eraser, and when the eraser is not in use, it may be concealed by the cap 24.

The magazines with leads are preferably each provided with a new eraser, but if desired the old eraser could be used with a new magazine until the eraser is entirely worn out before it is discarded. If the eraser is worn out before the supply of leads in the magazine is exhausted, the ferrule can be removed from the magazine and replaced by a new ferrule and eraser, or a new eraser may be placed in the ferrule. The leads are supplied to the user in the magazines 10, which serve as the container in which they are marketed and may be carried about in the pockets of the user, or may be stored without danger of breakage of the leads contained therein. They may be inserted into the pencil form by a very simple and rapid operation.

The plug 25 prevents the falling out of the leads when the ferrule is changed, and also compels the refilling of the magazine through the aperture between the tongues 17 of the cap 13 thereof, which is a rather slow process and would encourage the purchase of new magazines with contained leads rather than a supply of leads in some other form of container.

The use of the particular erasers, which are illustrated is also encouraged, by reason of the unusual mounting thereof.

In the claims, the sleeve 1 and casing 3 may be referred to as the barrel of the pencil, and the entire pencil without the maga-

zine may be referred to as the pencil form.

It will be obvious that various changes in the materials, details and arrangements of parts, herein described and illustrated for the purpose of explaining the nature of the invention, may be made by those skilled in the art within the principle and scope of the invention as expressed in the appended claims.

10 I claim:

1. A clutch pencil comprising a barrel, a clutch device at one end of the barrel through which leads are fed from the barrel and operable to clamp the leads therein at any portion of their travel by gravity through the clutch device, and a closed magazine containing a supply of leads insertable into and removable from the barrel at the end thereof opposite the clutch device, said magazine and barrel cooperating during the final movement of insertion of the magazine into the barrel to open the magazine, at its end adjacent the clutch device, automatically by the act of insertion, whereby the leads will be fed by gravity successively from the magazine into the clutch device.

2. A clutch pencil comprising a barrel, a clutch device at one end of the barrel through which leads are fed from the barrel and operable to clamp the leads therein at any portion of their travel by gravity through the clutch device, and a closed magazine containing a supply of leads insertable into and removable from the barrel at the end thereof opposite the clutch device; said magazine being closed at the end adjacent the clutch device by a wall which opens conically and outwardly when endwise pressure is applied to the peripheral portion thereof, said barrel having an internal seat against which the wall is thrust in the act of insertion of the magazine into the barrel and which acts upon the peripheral portion of the wall to open the magazine automatically and permit the contained leads to fall by gravity into the clutch device.

3. A clutch pencil comprising a pencil form having at one end means for gripping leads passing endwise therethrough from the interior of the form, and a magazine, insertable into and removable from the interior of the form, containing a plurality of leads, and having an end wall which opens outwardly when pressure is applied endwise thereto, the interior of the form at the end with the gripping means having an abutment cooperating with the said end wall to open it when pressure is created between the means and magazine, whereby the leads will be fed successively from the magazine into the gripping means.

4. A clutch pencil comprising a pencil form having at one end means for gripping leads passing endwise therethrough from

the interior of the form, and a magazine 65 insertable into and removable from the interior of the form, the form, in its interior and the magazine having cooperating parts for opening the magazine when pressure between them is created and allowing the leads 70 to fall by gravity successively through the gripping means.

5. A clutch pencil comprising a pencil form having at one end a lead gripping device with a lead conducting passage running 75 endwise therethrough from the interior of the form, and a closed magazine insertable into and removable from the interior of the form and containing a plurality of leads, the form having in its interior means to 80 open the magazine when pressure is created between the latter and said means by the act of embodying the magazine into the form, whereby the leads will feed successively from the magazine to the passage of the 85 gripping means.

6. A clutch pencil comprising a pencil form having at one end a lead gripping device with a lead conducting passage running endwise therethrough from the interior of 90 the form, and a magazine insertable into and removable from the interior of the form and adapted to contain a plurality of leads, one end wall of the magazine having a beveled corner, and a cap with a flat end wall closing 95 this beveled end of the magazine and having intersecting slits radiating from an interior point to the periphery thereof, the interior of the form having a frusto conical annular seat aligned with the beveled corner of the 100 magazine whereby when pressure is created between the capped end of the magazine and the seat as the magazine is embodied into the pencil form, the cap will be distorted conically and opened by a separation of the 105 points of the cap formed by the intersecting slits whereby the leads will be fed through the end cap into the passage of the gripping device successively.

7. A clutch pencil comprising a pencil form having at one end a lead gripping device with a lead conducting passage running endwise therethrough from the interior of the form, and a magazine insertable into and removable from the interior of the form and containing a plurality of leads, one end wall of the magazine having a beveled corner, a cap with a flat end wall closing this beveled end of the magazine and having intersecting slits radiating from an interior point to the periphery thereof, the interior of the form having a frusto conical annular seat aligned with the beveled corner of the magazine, whereby when pressure is created between the capped end of the magazine and the seat as the magazine is embodied into the pencil form, the cap will be distorted conically and opened by a separation of the points of the 110 115 120 125 130

cap formed by the intersecting slits, whereby the leads will be fed through the end cap into the passage of the gripping device successively, the internal opening of the magazine at the end closed by the cap being larger than the opening formed in the cap and disposed eccentrically thereof with a portion of its

wall aligned with a portion of the opening of the cap whereby the leads will be fed through the opening of the cap successively ¹⁰ without jamming.

In witness whereof, I hereunto subscribe my signature.

EDWIN CALDWELL.
